Application August 20, 1956, Serial No. 42,662

Term of patent 14 years

(Cl. D45—8)

FIG. 1

FIG. 2

FIG. 3

FIG. 4

Fig. 1 is a fragmentary plan view of an expandable chain for a bracelet or similar article, showing my new design, with portions thereof shown in broken lines for convenience of illustration;

Fig. 2 is a fragmentary plan view thereof, showing the chain in partially expanded condition;

Fig. 3 is an enlarged plan view of two of the links shown in Fig. 1; and

Fig. 4 is a side elevational view of two of the links of Fig. 1, with the conventional side walls thereof being shown in broken lines.

The pairs of links shown in full lines are repeated to provide an alternate arrangement of both types of links.

I claim:

The ornamental design for an expandable chain for a bracelet or similar article, substantially as shown and described.
